US00D732328S

(12) **United States Design Patent**
Bhutani et al.

(10) **Patent No.:** **US D732,328 S**
(45) **Date of Patent:** **** Jun. 23, 2015**

(54) **DISPENSER**

- (71) Applicant: **The Concentrate Manufacturing Company of Ireland**, Hamilton (BM)
- (72) Inventors: **Gurmeet Singh Bhutani**, Mohali (IN); **Tanmaya Vats**, Delhi (IN)
- (73) Assignee: **The Concentrate Manufacturing Company of Ireland**, Hamilton (BM)

(**) Term: **14 Years**

(21) Appl. No.: **29/475,958**

(22) Filed: **Dec. 9, 2013**

(51) **LOC (10) Cl.** **07-01**

(52) **U.S. Cl.**

USPC **D7/306; D7/311**

(58) **Field of Classification Search**

USPC D7/306, 307, 308, 309, 310, 311, 300, D7/305, 397; 222/108, 129.1, 129.2, 222/129.3, 129.4, 95; 99/295, 280, 285, 99/304, 307; D6/542, 543

CPC F04B 43/12

(57) **CLAIM**

The ornamental design for a dispenser, as shown and described.

DESCRIPTION

FIG. 1 is a top, front, right perspective view of a dispenser showing our new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

The broken lines shown in FIGS. 1-7, and the regions circumscribed by broken lines in FIGS. 1-7, form no part of the claimed design.

1 Claim, 6 Drawing Sheets
